US00D901533S

(12) **United States Design Patent** (10) **Patent No.:** **US D901,533 S**
(45) **Date of Patent:** **** Nov. 10, 2020**

(54) **DISPLAY SCREEN OR PORTION THEREOF WITH GRAPHICAL USER INTERFACE**

(71) Applicant: **Apple Inc.**, Cupertino, CA (US)

(72) Inventors: **Patrick Lee Coffman**, San Francisco, CA (US); **Raymond Sepulveda**, San Jose, CA (US); **Chun Kin Minor Wong**, Cupertino, CA (US)

(73) Assignee: **Apple Inc.**, Cupertino, CA (US)

(**) Term: **15 Years**

(21) Appl. No.: **29/723,756**

(22) Filed: **Feb. 10, 2020**

Related U.S. Application Data

(63) Continuation of application No. 29/692,223, filed on May 23, 2019, now Pat. No. Des. 875,127, which is a continuation of application No. 29/675,561, filed on Jan. 3, 2019, now Pat. No. Des. 854,574, which is a continuation of application No. 29/646,535, filed on May 4, 2018, now Pat. No. Des. 841,685, which is a continuation of application No. 29/582,383, filed on Oct. 27, 2016, now Pat. No. Des. 820,304.

(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE is a display screen or portion thereof with graphical user interface showing our new design.

The peripheral dashed broken lines illustrate a display screen or portion thereof, and form no part of the claimed design.
